DOOR OPERATING DEVICE

George Herbster, Cleveland, Ohio

Application April 15, 1936, Serial No. 74,501

8 Claims. (Cl. 126—192)

This invention relates to a device for opening and closing doors and the like and particularly to a treadle operated mechanism for both opening and closing doors of compartments such as cooking ranges, ovens and iceboxes by an operator while the operator is supporting in his hands articles to be placed within or removed from the compartment.

Specific additional problems are solved and advantages obtained by the use of the present invention in connection with downwardly swinging oven doors of domestic ranges, such as gas cooking ranges, or other relatively heavy doors having considerable inertia wherein problems other than those presented by the compartments in general are present. Accordingly, to more clearly present the problems, the present invention will be described specifically in connection with a domestic gas range cooking oven wherein the oven door swings downwardly about its lower edge to a horizontal position to permit access to the interior of the oven.

One of the objects of the present invention is to provide a treadle operated mechanism by which the oven door can be opened and closed selectively more conveniently so that the hands of the operator are free for other use and are not subjected to contact with the heated parts of the range.

30 A correlative object is to effect rapid and free movement of the door from either an open or closed position almost to the opposite position with effective buffing of the movement during final movement into such opposite position so as to prevent excessive shocks and strains and resultant damage to the door and parts of the range which commonly result when oven doors are slammed closed or open.

40 A more specific object is to accomplish these results with an oven drop door which is spring seated in closed position while at the same time eliminating any shocks due to rapid movement of the door by the spring.

Another object is to provide a dual treadle device for this purpose wherein, as either treadle is moved downwardly for operating the door, the other treadle is automatically raised to position for the opposite operation.

50 Other objects and advantages will become apparent from the following specification wherein reference is made to the drawings in which

Fig. 1 is a perspective view of a domestic gas cooking range with the present invention installed for use in connection therewith;

55 Fig. 2 is an enlarged vertical fragmentary sec-

tional view of the range with the present device installed and is taken on the plane indicated by the lines 2—2 in Figs. 1 and 4, respectively;

Fig. 3 is a horizontal sectional view taken on a plane indicated by the line 3—3 in Fig. 2;

Fig. 4 is a rear elevation of the operating mechanism and is taken on the plane indicated by the line 4—4 in Fig. 2, part of the associated range being shown in section;

Fig. 5 is a diagrammatic end elevation of the range illustrated in Fig. 1, showing the relative position of the present mechanism and one operating position thereof; and

Fig. 6 is an enlarged longitudinal sectional view of the dual buffering device of the present invention.

In Fig. 1 is illustrated a domestic gas cooking range 1 having a dual oven compartment, designated generally as 2, and having floors 2a and 2c which are closed at the front by a downwardly swinging comparatively heavy drop door 3. The range is supported on a suitable base frame 4 terminating at its lower edge in spaced relation above the floor of the room in which the range is located. As better illustrated in Figs. 2 and 4, the oven door 3 is pivotally connected adjacent its lower edge by means of a suitable pivot 5 to the frame of the range. The pivot or hinge 5 extends horizontally, lengthwise of the range, so that the door may swing thereabout from an upright closed position to a horizontal open position substantially on a level with the floor 2c of the oven, the horizontal position being indicated by the dotted lines in Fig. 2. For mounting the door on the pivot 5, there are mounted in the interior of the door, at each end, rigid supporting arms 6 which may be spot welded to the associated end walls of the door, internally thereof, the supports 6 receiving the pivot 5 at their lower ends. One arm 6 and co-operating parts are shown but it is to be understood that duplicate parts are used at opposite sides of the door and connected to the same treadle, later to be described.

Carried on and rigid with each support 6 is an arm 7 which is generally arcuate about pivot 5 as a center and provided near its free end with an abutment stop 7a. The stop 7a is positioned so that, when the door is in open horizontal position, the stop will abut the margin of the inner front wall 2b of the oven so as to arrest farther downward movement of the door. A coil spring 8 is secured by one of its ends to the arm 7, and the opposite end of the spring is connected to one of the frame members 9 of the range at

a point close to the interior wall surface of the front wall of the oven and near the oven floor so that the spring extends at a slight angle to the vertical when the door 3 is closed.

5 The spring 8 is tensioned sufficiently in its normal condition when the oven door is closed to hold the oven door firmly in closed position yet permit it to swing outwardly readily and fully vent any explosive pressure that might occur within the oven. That end of the spring 8 which is connected to the arm 7 is fastened thereto preferably close to the stop 7a so that when the door is in the open horizontal position, the spring 8 is positioned substantially vertically with its ends close to a vertical plane through the pivot 5 as a result of which its effective lever arm is too small to permit the spring to overcome the weight of the door from the horizontal position even though the spring is considerably stressed.

In some cases, as will later be described, a spring sufficiently strong for such swinging of the door from horizontal to upright position may be provided, but the structure above described 25 is customary in some of the newer types of domestic cooking ranges and the present invention is adapted for utilizing these existing parts as part of its own structure.

In this structure, the door 3 is held in upright 30 closed position by the spring 8 when moved into that position but remains horizontal when moved to the latter position. Obviously, however, a spring of sufficient strength to hold the door firmly closed will, if the door is given a slight 35 upward swing, continue the swinging of the door to closed position so forcefully that severe shocks and strains on the door and adjacent parts of the range will result. Likewise, since the spring preferably is too weak to raise the door from 40 horizontal position, it is not sufficiently strong to relieve the shock in event the door is given a quick or forceful swing downwardly. In both cases, there is considerable inertia developed. 45 Here again, the abutment 7a would be apt to damage the inner wall of the range or the door itself might be broken by the resultant shock. To overcome these objections and at the same time make possible the opening and closing of the door by foot operated mechanism so that the operator has both hands free to insert or withdraw articles from the oven, the mechanism now to be described is provided.

A link 10 is pivotally connected by one of its 50 ends to the arm 7 so as to swing in a plane parallel to the arm, the pivotal connection thereof to the arm 7 being indicated at 11. The link 10 preferably extends rearwardly from the plane of the oven door, and is pivotally connected at its 55 opposite end by a pivot 12 to a lever 13. The lever 13, in turn, is pivotally connected by a pivot 14 to a stationary bracket 15 secured to the frame of the range, the pivot 14 being disposed rearwardly from the plane of the oven door. The opposite end of the lever 13 extends 60 forwardly of the range substantially to the plane of the oven door but is positioned below the door, this end of the lever 13 being pivotally connected by a suitable pivot 16 to a tension rod or strip 17. The rod 17 extends downwardly 65 from the pivot 16 below the level of the oven floor 2a.

At its lower end the tension rod 17 is pivotally 70 connected by a pivot 18 to a treadle 19 which extends normal to the plane of the oven door and 75 is connected at the end which is remote from the

plane of the oven door by a pivot 20 to a bracket 21, the bracket being fixedly secured in position on the frame of the range. The treadle 19 extends forwardly from its pivotal connection with the rod and the outer end of the treadle is 5 shaped to provide a pedal portion 22, the treadle extending in front of the forward face of the range at one side of the oven door and is positioned preferably near the center of the range so as to be readily accessible to the foot of the operator and in position to be operated without danger of the door striking the operator.

Upon depressing the treadle by the foot of the operator, the treadle 19 swings about the pivot 13 downwardly and inwardly, thus drawing the 15 rod 17 downwardly and rocking the lever 13 about the pivot 14 so that the upper end thereof is moved forwardly. The link 10 is sufficiently rigid to transmit this forward motion to the door 3 so that when the pedal 22 is fully depressed, the door 3 is swung downwardly to fully 20 open horizontal position.

In order to close the door, a suitable treadle means is provided and comprises a tension rod 24 which is pivotally connected at its upper end 25 to the arm 7, preferably adjacent the stop 7a, as indicated at 25. The rod 24 extends downwardly below the floor level of the oven and passes between two guide rollers 26 which are mounted on the underside of a frame portion of 30 the stove. At its lower end the rod 24 is turned outwardly toward the front of the range and extends beyond the front plane of the range alongside of the treadle 19 and pedal 22, the extending portion being formed to provide a pedal 27. 35 Between the pedal 27 and the upper portion of the rod 24, the rod has a cam portion 28, this cam, in the form illustrated, being provided by suitably bending the rod 24. In the form illustrated, the cam portion 28 is shaped so that the 40 pedal 27 travels in a vertical path, though by changing the cam the pedal 27 can be made to move into substantially concealed position when the door 3 is closed. This is accomplished where desired, by coaction of the rollers 26 and cam 45 28 such that the rod 24 is swung rearwardly as it moves downwardly so that when the oven door is closed the pedal 27 is only slightly exposed, but when the oven door is open the pedal 27 is readily accessible for foot operation.

Obviously, if an operator should apply his 50 entire weight forcefully on either pedal, the movement of the relatively heavy door 3 would be so rapid that it would slam in extreme positions and probably break the hinges or damage the 55 range due either to the continued application of the weight or the inertia of the door even after the weight was removed. At the same time it is necessary that the door move very freely only under the influence of the spring 8 at and near 60 its closed position so that it may be held firmly but yieldably in closed position only by the spring 8.

In order that the door may swing very rapidly and freely throughout the greater portion of its 65 path of travel and yet be cushioned near the ends of its path of travel so that substantially no shock results and yet be capable of free and slower movement, into final position, a two-way buffer means is provided. In the form illustrated, the 70 buffer means comprises a cylinder 30 fixedly secured to the frame of the range. As better illustrated in Fig. 6, a piston 31 is reciprocable in the cylinder and is operatively connected by a piston rod 32 to the door of the oven. In the form of 75

the range illustrated wherein only limited space is permitted, the piston rod is operatively connected to the door 3 through the medium of the rod 17, and preferably extends as near as may be parallel to the direction of movement of the rod. 5 Since the rod 17 moves in a slight arcuate path, the upper end of the rod is connected, as indicated at 33, to a suitable pin 34 on the lever, a slight relatively pivotal movement being provided between the rod 33 and pin 34 to compensate for the slightly misaligned movement of the piston 31 and rod.

In the lower end of the cylinder 30 is a check valve 35 operable to admit air through a duct 36 into the cylinder at that end and to substantially prevent any movement of air in the opposite direction. A small spring seated check valve 37 is provided at the other end of the cylinder and is operable to admit air as indicated by the arrow 38 into the cylinder at the opposite end of the piston 31. The piston preferably fits the cylinder with a loose fit, slight clearances, as indicated by 39, being provided between the piston and cylinder wall. Consequently, the air cannot pass around the piston rapidly. Thus, throughout the initial portion of its path of travel in either direction, the door operates the piston against air at normal pressure and no compression of the air results until the door is moved both rapidly and an appreciable distance along its path. Upon extremely rapid or forceful movement of the door, and especially toward the end of its path of travel, the air between the piston and the particular end of the cylinder cannot escape rapidly enough and becomes compressed so as to eliminate shock and cushion the door. Since this air can leak past the piston, slower movement of the door is not resisted in any way. Due to the operation of the valves, both ends of the cylinder are assured of a supply of air at all times. Thus the cushioning effect is in a direct proportional relationship to the speed of travel of the door and permits substantially free initial movement of the door either slowly or rapidly.

As heretofore stated, the spring 8 is connected close to the plane of the door and the pivot 5 so that it acts so nearly through the pivot when the door is horizontal and offers substantially no resistance to the movement of the door. When the door is near upright position, however, the spring is disposed at a greater angle to a line from the point of connection 9 to the pivot 5 and may be capable of closing the door once it is swung partially toward closed position. With a buffer such as herein described utilized, this spring may be made much stronger for the purpose of closing the door once it is swung part way toward closing position.

Having thus described my invention, I claim:

1. In an apparatus having a compartment, a door hinged along one of the margins of the door for swinging about a horizontal axis to open and closed positions respectively, means yieldably urging the door to one of said positions, and pneumatic buffer means for resisting movement of the door in a direct proportional relationship to the speed of swinging of the door for preventing slamming thereof and operative to offer substantially no resistance to the swinging of the door when the door is moved more slowly toward said position, and operative during movement of the door along an intermediate portion of its path of travel to offer substantially no resistance to the movement thereof.

2. The combination with an apparatus having

a compartment and a door hinged along one of its margins for swinging about a horizontal axis to open and closed positions respectively relative to said compartment, and means yieldably urging the door to one of said positions, of buffer means 5 resisting movement of the door in a direct proportional relationship to the speed of movement of the door to check too rapid movement of the door and operative to offer substantially no resistance to the swinging of the door when the door 10 is moved more slowly toward said position.

3. The combination with an apparatus having a compartment and a door hinged along one of the margins of the door for swinging about a horizontal axis to open and closed positions respectively, of buffer means for yieldably resisting movement of the door by force in a direct proportional relationship to the speed of swinging of the door whereby too rapid swinging thereof is prevented, and operative to offer substantially 20 no resistance to the swinging of the door when the door is moved more slowly toward one of said positions, and operative during movement of the door along an intermediate portion of its path of travel to offer substantially no resistance to 25 the movement thereof.

4. The combination with an apparatus having a compartment and a door mounted on a horizontal pivot for swinging about the pivot to open and closed positions, and means to urge said door to 30 open and closed positions selectively, of double acting buffer means operative to resist movement of the door into final position in either direction when the door is moved rapidly toward such position and to permit free movement of 35 the door to such positions consequent upon a reduced speed of travel of the door to said positions.

5. In an apparatus having a compartment open at one upright face, a door pivoted about a horizontal pivot for swinging movement upwardly to upright position in closing relation to the open face and downwardly to horizontal position for permitting access to the interior of the compartment, a spring urging the door to 40 closed position, treadle means for closing said door, and buffer means yieldably opposing movement of said door to closed position near the end of its path of travel.

6. In an apparatus having a compartment open 50 at one upright face, a door pivoted about a horizontal pivot for swinging movement upwardly to upright position in closing relation to the open face and downwardly to horizontal position for permitting access to the interior of the compartment, treadle means for opening the 55 door, and buffer means yieldably opposing movement of the door rapidly along the final portion of its path of travel toward open position and permitting substantially unopposed movement 60 of the door more slowly to fully opened position.

7. In an apparatus having a compartment open at one upright face, a door pivoted about a horizontal pivot for swinging movement to upright position in closing relation to the open face 65 and to horizontal position for permitting access to the interior of the open compartment, a spring urging the door to closed position, treadle means for closing said door, and buffer means opposing movement of said door to closed position 70 near the end of its path of travel when the door is moved rapidly therealong toward such position and offering substantially no resistance to the door when the door is moved more slowly to said final position.

8. In an apparatus having a compartment open at one upright face, a door pivoted about a horizontal pivot for movement to upright position in closing relation to the open face and downwardly to horizontal position for permitting access to the interior of the compartment, pneumatic buffer means yieldably opposing movement of the door rapidly along the final portion of its path of travel toward one of said positions and being substantially unopposed to movement of

the door more slowly toward said one of said positions, said buffer means comprising a cylinder member, a piston member reciprocable therein, one of said members being operatively connected to the door for movement thereby relative to the other member, and restricted passage means for permitting escape of air from one end of the piston member to the other during relative movement of the members. 5

GEORGE HERBSTER. 10
